UNITED STATES PATENT OFFICE

LESLIE E. WOODSEND, OF LOS ANGELES, CALIFORNIA

WORK SUPPORTING ATTACHMENT FOR ABRADING MACHINES

Application filed March 6, 1929. Serial No. 344,766.

My invention relates to and has for a purpose the provision of a work supporting attachment for abrading machines particularly adapted, although not necessarily for use in the sharpening of the rotary cutter of a conventional meat grinding machine and the facing of the perforated disk or plate which confronts the rotary cutter in such a machine; my attachment being characterized by its capability of supporting and guiding these parts with respect to an abrading element such as a grinding wheel of a conventional grinding machine, in a manner to insure such accurate grinding of the cutter and disk that they will have maximum cutting co-action when in use.

I will describe only one form of work supporting attachment for abrading machines embodying my invention and will then point out the novel features thereof in claims.

In the accompanying drawings,

Fig. 1 is a view showing in side elevation a conventional abrading machine with one form of work supporting attachment embodying my invention associated therewith for the sharpening of the blades of a rotary cutter as used in certain meat grinding machines.

Fig. 2 is a view in end elevation partly broken away of the abrading machine and attachment shown in Fig. 1.

Fig. 3 is a plan view partly broken away of the attachment shown in the preceding figures, and in conjunction with a portion of the abrading machine.

Fig. 4 is a view in plan of a portion of a conventional abrading machine with the attachment embodying my invention as used in supporting and guiding the perforated disk or plate of a conventional meat grinding machine for facing of the disk, and

Fig. 5 is a view in end elevation of the abrading machine and the attachment shown in Fig. 4.

Referring specifically to the drawings in which similar reference characters designate similar parts in each of the several views, and particularly to Figs. 1 to 3 inclusive, my invention in its present embodiment com-

prises a base B preferably constructed of metal and of rectangular outline, to which is secured by bolts 10, a suitable power unit in the form of an electric motor M, the shaft 11 of which projects horizontally therefrom and has detachably secured thereto in any suitable manner an abrading element preferably in the form of a grinding wheel W, so that when the motor is in operation, the wheel will be rotated at a high speed to effect grinding of any work brought into contact therewith. The motor and grinding wheel constitute a conventional form of abrading machine, and the base B provides a common support therefor and for the work supporting attachment to be presently described.

The work supporting attachment comprises a cutter holder designated generally at H and including a body 12 in the form of a substantially rectangular block of metal having a non-circular socket 13 therein illustrated as being square in cross section. The body is provided with a bore 14 aligned with and communicating with the bottom of the socket 13; and through the bore is extendible the threaded shank 15 of a cutter supporting stud 16 having a non-circular portion 17 fitting the socket 13; a second and enlarged non-circular portion 18 on which a cutter C of conventional form is adapted to be supported; and a flat head 19 against which the cutter is adapted to abut for clamping between the head and body by means of a nut 20 on the shank 15.

The conventional cutter C as illustrated and used in certain types of meat grinding machines is in the form of a metal spider having four equally spaced radial arms constituting cutter blades 21 which are provided with cutting edges 22 extending lengthwise of the blades and disposed in one and the same plane for co-action with the perforated metal disk or plate 23 illustrated in Figs. 4 and 5, in effecting a cutting of meat as forced through the perforated plate, all of which will be understood by those familiar with the art. This cutter C is provided with a square axially disposed opening in which the non-circular portion 18 also illustrated as being square, is adapted to fit to support the cutter

on the stud 16 against rotation. The cutter is also recessed axially on its outer face to receive the head 19 of the stud so that the head is flush with the outer face of the cutter. 5 As the stud is prevented from rotating in the body 12 as a result of the co-acting non-circular socket 13 and the non-circular portion 17 fitting in the socket, the cutter will be clamped in a fixed position on the body with one of its cutter blades 21 projecting laterally from one side of the body as shown in Fig. 3 for sharpening of its cutting edge 22 by the abrading wheel W.

It will be clear that the position of the 15 cutter circumferentially with respect to the stud 16 or the position of the stud circumferentially with respect to the body 12 can be changed to dispose any one of the four cutting blades of the cutter in a single predetermined position for sharpening, due to the provision of the squared portions 17 and 20 25 18 of the stud and the co-acting square socket 13 and square axial opening in the cutter respectively, permitting the cutter to be adjusted circumferentially to occupy any one of four positions upon loosening of the nut 20 sufficiently to permit partial withdrawal of the stud 16 from the body 12.

The cutter holder H is adapted to be 30 mounted for such movement that a cutting blade 22 of the cutter carried by the holder can be presented to the abrading wheel in a manner to effect sharpening of the blade's cutting edge, and to this end I provide in 35 the present instance a projection 24 on the base B having a cylindrical bore 25 therethrough extending parallel to the axis of the shaft 11; and in the bore 25 is journaled for rocking movement and for sliding movement 40 longitudinally of the bore, a cylindrical extension 26 projecting laterally from and at right angles to an arm 27 having a squared portion 28 freely extending through a correspondingly shaped bore 29 formed in the 45 body 12, to thus support the cutter holder for sliding movement on the arm. To secure the holder in a fixed position on the arm a clamping screw 30 is threaded into the body 12 and bears against a flat surface of the 50 squared portion 28.

In the operation of the attachment thus far described, let it be assumed that the motor M is in operation and the cutter holder H with a cutter C secured thereto is secured in the 55 fixed position on the arm 27 as shown in Fig. 2. As the bore 25 is parallel to the axis of the shaft 11 and the cutter C is supported by the holder H with its cutting blades 21 disposed in a single plane also parallel to the 60 axis of the shaft 11, it will be clear that as the holder is grasped and the arm 27 swung towards the wheel W, the particular cutting blade 21 of the cutter C occupying the predetermined position above referred to will be presented flatwise to the peripheral sur-

face of the wheel and will extend transversely of the peripheral surface. With a cutter blade held in contact with the wheel W the blade is caused to move longitudinally back and forth across the peripheral surface of the 70 wheel, by shifting the arm 27 laterally in opposite directions to cause the extension 26 to slide longitudinally back and forth in the bore 25 so that the cutting edge 22 of the blade will be uniformly sharpened 75 throughout its length. Each of the four cutter blades 21 is sharpened in the same manner, it only being necessary each time another blade is to be sharpened, to adjust 80 the position of the cutter C circumferentially in the holder H to successively dispose each blade in the single predetermined position for sharpening. It will be noted that the body 12 is provided with a square projection 85 31 adapted to fit into the axial opening of the cutter C to fixedly support the latter in any one of four positions circumferentially so that the blades 21 of the cutter can be presented edgewise to the peripheral surface of the wheel W as shown in broken lines in 90 Fig. 3, for the removal of any feather edge remaining on the blades after sharpening.

In order to insure that the cutting edges 22 of all the blades 21 will be disposed in one and the same plane when the blades have 95 been sharpened, I provide a means for limiting the swinging movement of the arm 27 in presenting a cutter blade to the wheel W for sharpening. In the present instance this means comprises a post 32 having a squared lower end 33 removably fitted in a similarly shaped socket 34 formed in a boss 35 projecting upwardly from the base 13; the post being secured against displacement by means of a set screw 36 threaded into the boss 35 100 and bearing against the squared end 33 of the post. The post is provided adjacent its upper end with a transverse opening 37 of square cross-section in which is slidably mounted a square shank 38 of an abutment 39 in the form of a bar disposed in the path of swinging movement of the arm 27 in presenting a cutter blade to the wheel W, and extending lengthwise in a direction parallel 105 to the axis of the shaft 11. To secure the abutment 39 in a fixed position of adjustment 110 on the post, a set screw 40 is threaded into the latter and bears against the shank 38.

It will be clear that the abutment limits the movement of the arm 27 in presenting a cutting blade to the wheel, to a definite position so when all the cutter blades 21 have been sharpened, their cutting edges 22 will be disposed throughout their lengths in a single plane for maximum cutting co-action 125 with the confronting face of the perforated disk 23 previously referred to.

It will be noted that by changing the position of the cutter holder H along the length of the arm 27, the positions vertically, at 130

which the cutter blades 21 will be presented to the peripheral surface of the wheel W will accordingly vary so that the cutting edges of the blades when sharpened, will be relieved to a greater or less extent. As the amount of relief required for cutters of different diameters varies, it will be clear that this condition is compensated for by the adjustability of the holder on the arm; and to indicate position that the holder should occupy along the arm to obtain the amount of relief required for the particular size cutter to be sharpened, the squared portion 28 of the arm is preferably scored at predetermined intervals along its length as indicated at 41 for co-action with the body 12 in determining the proper position of the holder for each size cutter. The adjustability of the shank 38 in the post 32 permits the position of the abutment 39 to be varied to compensate for variations in the position of the holder H along the arm 27.

Referring now to Figs. 4 and 5, I have herein shown the manner in which my attachment is used for the facing or grinding perfectly flat of the side face of the perforated disk 23 which confronts the cutter C in the use of these parts in a conventional meat grinding machine. The holder H is removed from the arm 27, and for the holder is substituted a holder H¹ which comprises a bracket 42 having at one end a split clamping head 43 slidably receiving the arm 27 and adapted to be clamped to the latter by a co-acting threaded stud 44 and a nut 45. The opposite end of the bracket is provided with an arbor 46 of cylindrical form, which in the applied position of the holder H¹ to the arm 27 as shown in Fig. 1 extends lengthwise in a plane parallel to the axis of the shaft 11.

The conventional disk 23 is provided with a central hub 24 having therethrough an axial bore 45 receiving the arbor 46 to support the disk on the holder H¹ in parallelism with the outer side surface of the wheel W so that by simultaneously rocking the arm 27 about its axis and pressing the disk against the wheel W, the side of the disk confronting the wheel will be ground perfectly flat and true. In grinding the disk, the post 32 with the abutment 39 are removed so as not to interfere with the swinging movement of the arm 27. When the abrading machine is to be used for other purposes, the arm 27 can be removed from the base B by withdrawing its extension 26 from the bore 29 so that the abrading machine will be entirely unobstructed by my attachment.

Although I have herein shown and described only one form of work supporting attachment for abrading machines embodying my invention, it is to be understood that various changes and modifications may be made therein without departing from the spirit of the invention and the spirit and scope of the appended claims.

I claim:

1. An attachment of the character described comprising a body having non-circular socket, a cutter supporting stud having a non-circular portion on which a cutter is adapted to be mounted and a head against which the cutter is adapted to abut, the stud having a second non-circular portion fitting said socket, means for securing the stud to the body with a cutter on the stud clamped between the head of the stud and the body, and means for mounting the body for such movement with respect to an abrading element that a cutter carried by the body can be presented to the abrading element in a manner to effect sharpening of the cutter blade's cutting edge. 70

2. In a grinding machine having a rotary abrading wheel, an attachment therefor comprising a body having non-circular socket, a cutter supporting stud having a non-circular portion on which a cutter is adapted to be mounted and a head against which the cutter is adapted to abut, the stud having a second non-circular portion fitting said socket, means for securing the stud to the body with a cutter on the stud clamped between the head of the stud and the body, and means for mounting the body for such movement with respect to the abrading wheel that a cutter carried by the body can be presented to the abrading element in a manner to effect sharpening of the cutter blade's cutting edge, said means comprising an arm on which the body is supported, having a laterally projecting cylindrical portion, and means for mounting the cylindrical portion of the arm for rocking movement about an axis parallel to the axis of the abrading wheel and sliding movement in the direction of its length, and means for definitely limiting the rocking movement of the arm towards the abrading wheel. 90

3. In a grinding machine having a rotary abrading wheel, an attachment therefor comprising a body having non-circular socket, a cutter supporting stud having a non-circular portion on which a cutter is adapted to be mounted and a head against which the cutter is adapted to abut, the stud having a second non-circular portion fitting said socket, means for securing the stud to the body with a cutter on the stud clamped between the head of the stud and the body, and means for mounting the body for such movement with respect to the abrading wheel that a cutter carried by the body can be presented to the abrading element in a manner to effect sharpening of the cutter blade's cutting edge, said means comprising an arm of non-circular cross section on which the body is slidably mounted, means for fixedly securing the body to the arm against sliding movement, the arm having a laterally projecting cylindrical portion, and means for mounting 110

115

120

125

130

the cylindrical portion of the arm for rocking movement about an axis parallel to the axis of the abrading wheel and sliding movement in the direction of its length, and means for definitely limiting the rocking movement of the arm towards the abrading wheel.

4. An attachment of the character described comprising a body having non-circular socket, a cutter supporting stud having a non-circular portion on which a cutter is adapted to be mounted and a head against which the cutter is adapted to abut, the stud having a second non-circular portion fitting said socket and a threaded shank extending through the body, a nut threaded on the stud for co-action with the head of the stud in clamping a cutter on the stud between the head and body, and means for mounting the body for such movement with respect to an abrading element that a cutter carried by the body can be presented to the abrading element in a manner to effect sharpening of the cutter blade's cutting edge.

5. In an attachment of the character described, a cutter holder comprising a body having a non-circular socket, a cutter supporting stud having a non-circular portion on which a cutter is adapted to be mounted and a head against which the cutter is adapted to abut, the stud having a second non-circular portion fitting said socket, and means for securing the stud to the body with a cutter on the stud clamped between the head of the stud and the body.

6. In an attachment of the character described, a cutter holder comprising a body having a non-circular socket, a cutter supporting stud having a non-circular portion on which a cutter is adapted to be mounted and a head against which the cutter is adapted to abut, the stud having a second non-circular portion fitting said socket and a threaded shank extending through the body, and a nut threaded on the shank for clamping a cutter on the stud between the head of the stud and the body.

7. In an attachment of the character described, a cutter holder comprising a body having a non-circular socket, a cutter supporting stud having a non-circular portion on which a cutter is adapted to be mounted and a head against which the cutter is adapted to abut, the stud having a second non-circular portion fitting said socket, and means for securing the stud to the body with a cutter on the stud clamped between the head of the stud and the body, the body having a non-circular projection on which the cutter is adapted to be mounted.

60 LESLIE E. WOODSEND.
